UNITED STATES PATENT OFFICE.

WILLIAM L. BEATON, OF HALLOCK, MINNESOTA.

ATTACHMENT FOR GANG CHEESE-PRESSES.

SPECIFICATION forming part of Letters Patent No. 398,932, dated March 5, 1889.

Application filed August 31, 1888. Serial No. 284,224. (No model.)

To all whom it may concern:

Be it known that I, WILLIAM L. BEATON, a citizen of the United States, residing at Hallock, in the county of Kittson and State of Minnesota, have invented certain new and useful Improvements in Attachments for a Gang Cheese-Press; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to gang cheese-presses, and has for its object the provision of an attachment for holding the cheese-hoops in alignment when pressure is brought to bear and guiding them in their movement.

20 The improvement consists in the novel features which hereinafter will be more fully described and claimed, and shown in the annexed drawings, in which—

Figure 1 is a perspective view of a gang cheese-press of well-known construction embodying my invention; Fig. 2, a vertical cross-section about on the line $x-x$ of Fig. 1; Fig. 3, a perspective view of one of the yokes or cross-bars, and Fig. 4 is a cross-section of a longitudinal half of the press on the line $z-z$ of Fig. 1. Fig. 5 is a detail view showing a modification in which the pins are inserted in the beams and come flush with the tops thereof, finger-notches being provided to permit the ready removal of same.

The gang-press herein shown is of well-known construction and is shown simply to illustrate the application of my invention.

The attachment, composed of the series of 40 longitudinal strips A and the cross-bars B, is secured to the frame of the press in any convenient manner, preferably by the vertical short bars C, which are hinged at their upper ends to the said cross-bars and are bolted to the frame. The hasps D, hinged to the opposite ends of the cross-bars, are adapted to fit over staples e on the press-frame and hold the attachment down. There are two pairs of these longitudinal strips A, each pair corresponding to the hoop-guides G G' of the frame. The opposing edges of each pair of strips are

beveled to give clearance for the cheese-hoops, and are adjustably connected with the cross-bars by the bolts d, passing through the strips A and through elongated perforations b in the 55 cross-bars, and the thumb-screws E, screwed on the ends of the bolts d. The cross-bars are arched at f f' to give clearance for the cheese-hoops.

The frame of the press, which is of ordinary 60 construction, comprises a middle and side beams, G and G', respectively, which form guides and hold the cheese-hoops against lateral displacement, and two pairs of bars, K and K', for supporting the two rows of cheese-hoops from below. The nuts I, of well-known 65 construction, are adjustably held to the beams by the pins g, which pass through one of a series of openings in each of the said beams in the usual and well-known manner. The strips 70 A have openings corresponding with the openings in the beams G and G', so that the pins g can be removed and the nuts I adjusted without raising the attachment. In some instances the holes in the strips may be dispensed with, and the pins g will come flush with the tops of the beams, finger-notches being provided to grasp the ends of the pins when it is desired to remove them.

In practice the attachment is turned up out 80 of the way, and after the cheese-hoops to the desired number are placed in the guides in the frame the attachment is turned down and secured by the hasps D, which are fitted over the staples e. The upper portions of the cheese-hoops fit between the opposing edges of the strips, which hold the said hoops down and prevent their bulging or getting out of alignment, and also guide the hoops in their movement.

Having thus described my invention, what I claim, and desire to secure by Letters Patent, is—

1. In a gang-press of the herein-described type, the combination, with the frame having 95 guides, of the guide attachment composed of longitudinal strips and cross-bars, the said strips being arranged to come over the said guides, substantially as described, for the purposes specified.

2. The combination, with the frame having guides, of the attachment composed of longi-

- tudinal strips and cross-bars, the strips being arranged in pairs and having the opposing edges of each pair of strips beveled, substantially as described, for the purposes specified.
- 5 3. The combination, with the frame having a guide, of the cross-bars, and the pair of longitudinal strips adjustably connected with the cross-bars, substantially as described, for the purposes specified.
- 10 4. The combination, with the frame having a guide, of the cross-bars arched opposite the said guide and having elongated openings, the longitudinal strips, and the bolts and the set-screws adjustably connecting the strips with the cross-bars, substantially as described, for the purposes specified.
- 15
5. The combination, with the frame having a series of parallel guides, of the cross-bars arched opposite the guides and having elongated openings each side of the said guides, 20 the short vertical bars hinged to the cross-bars at one end, the hasps hinged to the other ends of the cross-bars, the longitudinal strips arranged in pairs, and the bolts and thumbscrews for adjustably securing the strips to 25 the said cross-bars, substantially as described.

In testimony whereof I affix my signature in presence of two witnesses.

WILLIAM L. BEATON.
